PLASTIC BOBBIN

Paul B. Wilson, Portland, Oreg., assignor to
Harold D. Wolgamot, Portland, Oreg.

Application July 5, 1945, Serial No. 603,337

2 Claims. (Cl. 242—120)

1

This invention relates to a bobbin, quill or cop for textile machinery and more especially to a bobbin, quill or cop made of plastic material such as "Tenite" which is cellulose aceto-butyrate. The object of the invention will hereinafter be referred to under the broad term "bobbin." This bobbin is designed to overcome many of the imperfections and bad qualities of a wood bobbin universally heretofore employed in the textile trade such as in spinning frames and the like.

In wooden type bobbins having the three rings clamped therearound which are employed for enabling the bobbin to be held in a shuttle in an automatic loom, when the base of the bobbin cracks due to the fact that the bobbin is forced down over the tapering spindle in a spinning frame, the centrifugal force of the spindle, running from fifteen to twenty thousand revolutions per minute in the spinning frame, will cause the base to spread, thereby losing friction and not give the required number of revolutions per minute, thus resulting in the yarn's not receiving the required number of twists per inch. In the present bobbin the solid metallic band which is disposed around the base of the bobbin has three circular projections thereon to take the place of the conventional wire rings clamped around the wooden base of the bobbin and, therefore, prevents any expansion of the bobbin base.

Further, this metallic band being around the base of the bobbin and the plastic material being molded to the band thus embedding the band in the periphery of the bobbin base renders the band and its circular projections thereon incapable of shifting its position relative to the base, and therefore the bobbin will always align itself when projected into the shuttle so that the tip of the bobbin will be at the same point relative to the eye of the shuttle at all times.

Furthermore, the steel rings which are clamped around the bases of wooden bobbins will slide around the base of the bobbin and, as is well known, these steel rings have a gap between their ends and two and sometimes three of the gaps in these steel rings will be in alignment vertically of the bobbin and thus will not properly hold the bobbin when it is snapped into the shuttle and will allow its point to not be centered with the eye of the shuttle. Also because of the difference in the density of wood at various spots, it is impossible to make a really balanced bobbin which always results in the bobbin being out of balance, which will cause it to shake loose from its frictional contact with the spindle resulting in defective yarn or requiring stoppage of the machine.

Furthermore, because of the difference in the density of the various portions of a piece of wood out of which a quill or a bobbin is turned, it is impossible to make a perfectly round bobbin, that is, one which is a perfect circle in cross section,

2

and thus any wooden bobbin will be out of balance on account of the fact that it is not perfectly round as varying resistances are offered by the wood to the cutting tool which cuts out the bobbin from a block of wood.

Furthermore, it is impossible to make a perfectly round bore in the base of a wooden bobbin, because of the difference in density of the various spots of the wood, whereas in plastic this bevel can be perfectly molded, and will not wear unevenly like wood.

Furthermore, the salvage value of a plastic bobbin is quite an item as it can be remelted and remolded into a new bobbin, whereas a wooden bobbin must be discarded.

Because of the resilient nature of plastic material such as "Tenite," even when it is dented from abuse, within at most a day or so, the dent seems to have a tendency to fill back out and present a smooth surface.

Furthermore, it is much harder to dent or damage than a wooden bobbin and, even if dented to a point where it will not return to its shape completely, there are no protruding fibers as in a wood bobbin to catch the yarn being processed thereon.

A plastic being of uniform density throughout and molded in perfectly round cross section will always present a balanced bobbin, the base will always properly grip the spindle and also, the bobbin is much harder to damage as to the surface thereof and will always present a smooth surface for receiving the yarn. Also, the metallic band, such as a steel band, which is embedded around the base of the bobbin and the bobbin molded to the band does not provide any gap whatever for misalignment of the bobbin in the shuttle.

It is, therefore, an object of this invention to provide a bobbin molded from plastic material such as cellulose aceto-butyrate, commonly known in the trade as "Tenite."

It is another object of this invention to provide a bobbin molded from plastic material throughout and having a metallic ring with a plurality of separate projections around its base permitting it to be used as a loom bobbin.

Some of the objects of the invention having been stated, other objects will appear as the description proceeds when taken in connection with the accompanying drawings in which:

Figure 1 is side elevation of my improved bobbin;

Figure 2 is a vertical sectional view through the bobbin;

Figure 3 is a transverse sectional view substantially along the line 3—3 in Figure 1;

Figure 4 is a cross-sectional view taken along line 4—4 in Figure 1;

Figure 5 is a vertical sectional view taken

through the lower portion of the bobbin and on an enlarged scale.

Referring more specifically to the drawings the numeral 10 indicates the base portion of the bobbin while the numeral 11 indicates the barrel portion. This barrel has a plurality of grooves 12 therearound and a plurality of inverted truncated portions 13 to provide the proper configuration for receiving the yarn in a spinning frame and the like.

The entire base portion 10 and the barrel 11 is molded from a suitable plastic such as cellulose aceto-butyrate commonly known in the trade as "Tenite" and manufactured by Tennessee Eastman Corporation.

The bobbin has a plurality of wires 14 extending from near one end to the other and around these wires is disposed a tubular woven metallic wire member 15. The woven wire tube 15 is disposed around the longitudinally extending wires 14 and then a suitable metallic ring 16 is disposed in the mold in the proper position and with the wires 14 and wire tube 15 in position the plastic material is poured into the mold and the same is molded under pressure to thereby provide a reinforced plastic bobbin with the entire inner and outer surfaces being of continuous plastic material and the only portion on the outer surface which is not of plastic material is the metallic ring 16 having the three raised circular projections 18 on its exterior for fitting into the bobbin holding mechanism in a shuttle.

The bobbin has a bore 19 extending from end to end, the lower end of the bore being larger than the upper end of the bore, it being stepped off as shown in the drawings, which is conventional in wooden bobbins. The lower end of the bore 19 is adapted to fit over a beveled portion of a conventional spindle, whereby by frictional engagement with the spindle the bobbin will be driven by the spindle in a spinning frame and the like. The plastic material forms a perfectly true circle in the lower end of the bore for engaging the tapered portion of the spindle and therefore precludes any possibility of the bobbin's coming loose on the spindle. Also, since the plastic material is uniform in density through-

out, a perfectly balanced bobbin is provided which will run true at all times on the spindle even at high speed, and furthermore, the annular member 16 being molded into the plastic base 5 cannot expand and allow the base to expand and thus decrease the frictional contact between the lower end of the bore 19 and the tapered portion of the spindle in the spinning frame.

In the drawings and specification there has been set forth a preferred embodiment of the invention, and although specific terms are employed, they are used in a generic and descriptive sense only, and not for purposes of limitation, the scope of the invention being defined in the claims.

15 I claim:

1. A bobbin molded from cellulose aceto-butyrate and having reinforcing metallic members extending from one end of the bobbin to the other and completely embedded within the cellulose aceto-butyrate and said reinforcing members being incased by a metallic tube of screen wire and the like, and the metallic tube and reinforcing wires extending longitudinally of the bobbin being completely embedded within the bobbin and not exposed to the interior or exterior surface of the bobbin.

2. A bobbin molded from plastic material and having reinforcing metallic members extending from one end of the bobbin to the other and completely embedded within the plastic material and said reinforcing members being incased by a metallic tube of screen wire and the like, and the metallic tube and reinforcing wires extending longitudinally of the bobbin being completely embedded within the bobbin and not exposed to the interior or exterior surface of the bobbin.

PAUL B. WILSON.
